(71) Applicant: **Advanced Powertrain Engineering, LLC**, Sullivan, IN (US)

(72) Inventor: **Paul Fathauer**, Sullivan, IN (US)

(73) Assignee: **Advanced Powertrain Engineering, LLC**, Sullivan, IN (US)

(**) Term: **15 Years**

(21) Appl. No.: **29/540,243**

(22) Filed: **Sep. 22, 2015**

(57) **CLAIM**

I claim the ornamental design for a printed circuit for an automatic transmission solenoid module, as shown and described.

DESCRIPTION

FIG. 1 is a front view of the of my new design; and, FIG. 2 is a back view thereof.

The top, bottom, right side, and left side views form no part of the claimed design.

1 Claim, 2 Drawing Sheets
